UNITED STATES PATENT OFFICE.

LLOYD GROFF COPEMAN, OF FLINT, MICHIGAN.

SAFETY DEVICE FOR ELECTRICALLY-HEATED COOKING APPARATUS.

1,113,154.

Specification of Letters Patent.

Patented Oct. 6, 1914.

Application filed December 23, 1911. Serial No. 667,530.

To all whom it may concern:

Be it known that I, LLOYD GROFF COPEMAN, a citizen of the United States of America, residing at Flint, in the county of Genesee and State of Michigan, have invented certain new and useful Improvements in Safety Devices for Electrically-Heated Cooking Apparatus, of which the following is a specification, reference being had there-

10 in to the accompanying drawings.

The invention relates to electrically-heated cooking apparatus, and it is the object of the invention to guard against dangerous overheating of the apparatus through the 15 accidental continuance of the electric heat generation when the device is not in use. Heretofore various forms of thermostats have been applied to apparatus of this kind, which are designed to break the electric circuit by the mechanical operation of a switch 20 thermostatically controlled. It is also customary to guard the electric circuits by fuses. These do not, however, effectually prevent overheating, for the reason that 25 thermostatic devices are uncertain in their operation and the electric fuses are only blown where there is an abnormal flow of current therethrough.

With the present invention I secure safety 30 by guarding the electric circuits with low-fusing connectors which will be broken by abnormal external heating but which are sufficiently low in resistance to avoid blowing electrically. These fusible connectors 35 are located in fireproof and electrically insulated casings, and are so positioned that any abnormal heating effect which might be injurious will cause the melting of the fuse and the consequent breaking of the circuit.

40 In the drawings, Figure 1 is a diagram of an apparatus including the safety device; and Fig. 2 is a perspective view of the casing and fusible link.

45 As shown diagrammatically in the drawing, A is the cabinet of a fireless cooker, within the chamber B of which is arranged an electric heating unit C.

D is the service conductor for the electric current, and E is an electric switch controlling the same.

My safety device is located in any position where it will be exposed to heat either conducted or radiated from the chamber B, such for instance as shown in Fig. 1 where it is placed in the top of the cabinet. Preferably each lead of the electric circuit is 55 guarded by a fuse, and these fuses are arranged in separate chambers so as to avoid all danger of short circuiting. As illustrated, F is a casing formed of porcelain 60 or other fire proof and electrical insulating material, being of any suitable shape, such, for instance, as an ordinary rosette, G are the electric contacts and H is the fusible connector which is coupled to the contacts 65 G and is inclosed between the upper section F of the rosette and the base F' thereof.

In operation the current supply to the heating unit C normally passes from the leads D through the fuses H which are sufficiently low in resistance to avoid any danger of being electrically blown. When however, an abnormal heat is developed 70 within the chamber B and is communicated therefrom to the casing F the fuse links H 75 which are of low melting point, will be broken interrupting the current and preventing further heating.

What I claim as my invention is:

In an electrically heated apparatus, the 80 combination with a heat insulated chamber, of an electric heater therein, an electric circuit in which said heater is connected, and a fusible link included in said circuit of sufficiently high electrical conductivity to avoid 85 fusion from internally generated heat and of relatively low fusing point, said link being positioned on the opposite side of said chamber from said heater and exposed to heat conducted or radiated from said chamber, and adapted to be fused by an abnormal 90 heating of the contents of the chamber.

In testimony whereof I affix my signature in presence of two witnesses.

LLOYD GROFF COPEMAN.
